UNITED STATES PATENT OFFICE.

HARRY BARD, OF MILLVILLE, NEW JERSEY, ASSIGNOR TO MILLVILLE MACHINE COMPANY, OF MILLVILLE, NEW JERSEY, A CORPORATION OF NEW JERSEY.

MOLD FOR GLASS-BLOWING MACHINES.

No. 800,352.

Specification of Letters Patent.

Patented Sept. 26, 1905.

Application filed July 14, 1903. Serial No. 165,471.

To all whom it may concern:

Be it known that I, HARRY BARD, a citizen of the United States, and a resident of Millville, Cumberland county, New Jersey, have 5 invented certain Improvements in Molds for Glass-Blowing Machines, of which the following is a specification.

The object of my invention is to provide a bottom member for the blow-molds of glass-blown machines arranged to be automatically lifted into position when the mold is closed and to be automatically depressed and lower the article of hollow glassware under process of manufacture when the mold is 15 opened. The use of such a bottom provides greater ease in removing the article, and the danger of breakage is reduced to a minimum.

My invention is fully shown in the accompanying drawings, in which—

20 Figure 1 is a sectional elevation of a press and blow-mold made in accordance with my invention. Fig. 2 is a plan view of the same. Fig. 3 is a sectional elevation on the line *a a*, Fig. 1. Fig. 4 is a side elevation of the press and blow-mold structure as shown in Fig. 1, and Fig. 5 is a perspective view of the blow-mold bottom and the mechanism for operating the same.

As shown in the present instance, the bottom 30 which I have devised is designed for use in connection with large-mouthed bottles, the particular style of bottle to be made by the mold shown herewith being the familiar one-quart milk-bottle. It will be understood, however, that with the usual and ordinary changes 35 of size and shape my improved form of mold may be used with any style of bottle. Hitherto in the manufacture of bottles of this and other characters there has been more or less difficulty encountered in removing the bottle after it has been blown. To overcome this 40 more or less serious difficulty and at the same time to provide a bottom mold-section that would insure a true base or bottom for the bottle, I have arranged the bottom of the mold structure as an independent member and provide mechanism whereby it may be raised as the mold is closed and depressed, carrying 45 with it the molded bottle when the latter has 50 been finished.

In the drawings herewith, 1 represents the blow-mold structure comprising the half-sections 2, which are carried by studs 3, movable

transversely across the traveling bed 4 by means of a cam-plate 5, having a suitable 55 handle 6 pivotally mounted in the bracket 7. The bed-plate 4 is slotted at 8 for the passage of the studs, which are threaded into the sections 2 of the mold. The mold-sections, therefore, are not hinged together, but are movable laterally and open entirely free when it is desired to remove the bottle. A catch-piece 9, carried by the bed-plate 4, is provided to engage the handle and insure that the mold will remain closed when the handle is moved 65 over into the position shown in Fig. 2. The cam-plate 5 is suitably journaled at the center on a stud 10 and is provided with a pair of curved slots 11, in which the studs 3 are disposed.

70 Centrally disposed with respect to the mold-section 2 and mounted in the base-block 15 is the movable bottom 16 of the mold, which is secured to and supported by means of a series of pins 17, which pass through the table or 75 bed-plate 4, upon which the mold structures are mounted, and engage curved cam-grooves 18, formed in the upper face of the cam-plate 5. These pins are held by the base-block 15 against lateral movement, but are free to rise 80 and fall within the same, depending upon the position of the cam-plate, the latter serving to raise the pins and through them the bottom mold to which they are secured, while the latter assumes the lower position as soon as the 85 mold is open, under the influence of gravity. When in the closed position, the bottom mold member will be raised into the operative position, as illustrated in Figs. 1, 2, 3, and 5, the pins carried thereby being lifted to the 90 high portion of the cam-grooves by the turning of the cam-plate 5. The base-block 15 serves as a guide for the half-sections 2 when the mold is opened and closed and is slotted at 95 for the passage of the studs 3.

The base-block has a flange surrounding the opening for the movable bottom, and the lower inner edge of the half-sections of the blow-mold is undercut to engage this flange, which thereby positions said sections with 100 respect to the bottom. The bottom has an outer rim which engages the under surface of the undercut portion of the half-sections of the mold so that the curved surface of said bottom will register with the inner wall of 105 said mold-sections.

The action of closing or opening the mold and lifting or depressing the bottom mold member, respectively, will be simultaneous, as both actions are controlled by the cam-plate 5, having the pivoted handle 6.

The press-mold shown at 20 and carried by the traveling bed-plate 4 may be of any approved form suitable for preparing the charge of glass to enter the blow-mold and receive the air under pressure.

Having thus described my invention, I claim and desire to secure by Letters Patent—

1. The combination in a blow-mold for glass-blowing machines, of the half-sections of the same, means for supporting said sections, studs carried by the same, a cam-plate having slots in which said studs are disposed, such arrangement serving to open or close the mold as said cam-plate is moved, an independent bottom for said mold, and means for raising said bottom into the operative position by the action of the cam-plate when the half-sections of the mold are closed.

2. The combination in a blow-mold for glass-blowing machines, of the laterally-movable half-sections, a movable bottom member for the mold, a cam-plate having curved slots therein, studs carried by the half-sections and engaging said curved slots whereby said half-sections may be opened and closed by the movement of the cam-plate, depending pins carried by the bottom member, and a series of cam-grooves carried by the cam-plate for

engaging the pins of the bottom member whereby the latter may be lifted into the operative position simultaneously with the closing of the half-sections of the blow-mold.

3. The combination in a blow-mold for glass-blowing machines, of a vertically-movable bottom member, depending pins carried by the same, a cam-plate, cam-faces carried thereby for engagement with said pins whereby the bottom may be raised into the operative position, and means for moving and locking said cam-plate.

4. The combination of the laterally-movable half-sections of the blow-mold having their lower inner edge undercut, a base-block serving as a guide for the same and having a flange engaging the undercut portion of the blow-mold sections when they are closed, a bottom member mounted within said base-block and movable into and out of position with relation to the half-sections, said bottom having an outer rim which fits in the undercut portion of the half-sections of the blow-mold, and means for closing said sections and simultaneously raising the movable bottom member into place.

In testimony whereof I have signed my name to this specification in the presence of two subscribing witnesses.

HARRY BARD.
